(57) **CLAIM**

The ornamental design for a camera with flip-open display, as shown and described.

DESCRIPTION

FIG. 1 is a perspective view of a camera with flip-open display showing our new design;

FIG. 2 is a right side elevational view thereof;

FIG. 3 is a front elevational view thereof;

FIG. 4 is a top plan view thereof;

FIG. 5 is a left side elevational view thereof;

FIG. 6 is a rear elevational view thereof; and,

FIG. 7 is a perspective view thereof showing the display in a flipped open position.

The broken lines shown in FIGS. 5 and 6 are for illustrative purposes only and form no part of the claimed design.
